CLAIM

The ornamental design for an on-board diagnostics module, as shown and described.

DESCRIPTION

FIG. 1 is a perspective view of an on-board diagnostic module showing our new design;

FIG. 2 is a bottom view of the on-board diagnostic module of FIG. 1;

FIG. 3 is a top view of the on-board diagnostic module of FIG. 1;

FIG. 4 is a left side view of the on-board diagnostic module of FIG. 1;

FIG. 5 is a right side view of the on-board diagnostic module of FIG. 1;

FIG. 6 is a front side view of the on-board diagnostic module of FIG. 1; and,

FIG. 7 is a back side of the on-board diagnostic module of FIG. 1.

1 Claim, 5 Drawing Sheets(56)
